UNITED STATES PATENT OFFICE

ALFRED YUDES, OF BELLEROSE, NEW YORK

FASTENING DEVICE FOR A WINDOW

Application filed October 24, 1930. Serial No. 490,845.

This invention has to do broadly with the art of windows and is more particularly concerned with a novel type of window construction designed to permit of swinging movement of the window in addition to the usual sliding action.

At the present time such propositions as the washing of windows, the replacement of broken window-panes, and other similar work exposes the persons carrying out such work to some little danger due to the fact that it is necessary to climb out into position in which access may be had to the exterior surface of the window-pane. With this condition in mind, this invention has in view as its primal object the provision of a window construction which includes the two sash frames that slide up and down in the usual manner but which are mounted in the window frame so as to afford not only the sliding action, but also a swinging movement which may be effected to position either or both of the sash frames in a position in which the exterior surface thereof is accessible from the interior of the building in which the window is located.

In carrying out this idea in a practical embodiment, certain problems arise which must be properly taken care of in order to provide a commercially feasible construction. In order to provide the swinging action on the part of the sash frames, it is necessary that they be pivotally mounted at one side. Such pivotal or hinge connection in itself is not adequate to provide a good seal against weather conditions which heretofore has been afforded by the conventional slide and groove constructions. In accordance with this invention a weather strip arrangement is availed of in conjunction with the hinged mounting and which arrangement affords an effective seal against the weather when the window sash is in closed position.

Another consideration of importance is the provision of mechanism that affords a tongue and groove construction at one side of the window sash and frame which may be operated to withdraw the tongue from the groove to permit of swinging movement on the part of the window sash. This mecha-

nism constitutes for all effective purposes a latching or locking device which normally maintains the window sash in slidable position in the frame, but which may be operated when it is desired to swing the sash inwardly to provide access to the exterior surface thereof.

A somewhat more detailed but nevertheless important feature of the invention is associated with the provision of hinge and latch devices for each of the window sashes, which devices may be operated under all conditions regardless of the position of the sashes in the frame. More particularly, it is my idea to render both the upper and lower sashes swingable inwardly for any position which they may assume in the frame, that is, the lower frame may be swung inwardly when in an upraised position, while the upper or outer sash may be swung inwardly while in a lowered position.

Other more detailed objects and advantages of the invention are associated with the provision of properly operable hinge and latch devices together with the mounting of these devices in the sash and frame constructions. These will in part become apparent and in part be hereinafter stated as the description of the invention proceeds.

For a full and more complete understanding of the invention, reference may be had to the following description and accompanying drawings wherein:

Figure 1 is a view in front elevation of a window construction embodying the improvements of this invention;

Fig. 2 is an enlarged detail horizontal section taken through the upper portion of the window construction about on the plane represented by the line 2-2 of Fig. 1. In this view parts are broken away to permit of the showing of the construction at each side on an enlarged scale;

Fig. 3 is a showing somewhat similar to Fig. 2 but is taken about on the plane represented by the line 3-3 of Fig. 1;

Fig. 4 is a fragmentary showing on an enlarged scale with parts broken away and shown in section and elevation, of the locking mechanism which normally maintains

the window in sliding position but which may be operated to permit of the swinging action;

Fig. 5 is a diagrammatic showing, also on an enlarged scale, with parts broken away to more clearly bring out the details of the locking device. This view is in perspective;

Fig. 6 is another perspective showing bringing out the position of the parts at the hinged side of the window sash when the latter is swung inwardly; and

Fig. 7 is a fragmentary plan view taken at one end of the window frame.

Referring now to the drawings, a window frame of conventional design is shown in Fig. 1 and designated generally A. This frame A may be of any preferred construction which provides the structure necessary for the operation of the sashes therein. In this connection it is notable that the invention is herein described as being incorporated with a frame and sash arrangement made from wood, but the invention is not intended to be limited in this respect, as it is just as susceptible of being employed in conjunction with metallic window constructions.

Operatively mounted in the frame A in a manner to be hereinafter described in detail are lower and upper sashes B and C which are intended to have sliding and swinging movements in accordance with this invention.

The frame A comprises a top piece shown at 10 which is connected to a bottom piece 35 or sill designated 11 by side or frame members 12 and 13. The connections between these parts 10, 11, 12, and 13 may be of any suitable design and in the present instance are shown as consisting of miters 14. Carried by the top piece 10 are a pair of spring devices referred to generally as 15 and 16 which constitute a means for counterbalancing the weights of the sashes B and C, the spring device 15 being operatively associated with the sash B, while the device 16 is connected up with the sash C. It is to be clearly understood that while the sashes are herein shown as being counterbalanced by the spring arrangements, the invention is not to be specifically identified with these spring arrangements, as the invention could well be availed of in conjunction with the old well-known weight arrangements already employed for the purpose of counterbalancing the window sashes.

The spring devices 15 and 16 are of duplicate construction, so only one of them is described for the purposes of this specification. Referring now more particularly to Figs. 1 and 7, it is noted that a bracket 17 is secured to the upper surface of the top piece 10 in any suitable manner, such as by screws designated 18. This bracket 17 has up-turned ends 19 and 20 which are provided with openings 21. A shaft 22 extends through

the openings 21 and carries at the end adjacent the upright portion 20 a winding drum 23. This shaft 22 is maintained in assembled relation with respect to the bracket 17 by the coordinated effects of the drum 23 and a nut 24 threaded on the other end of the shaft. A cord indicated at 25 is taken up on the drum 23 and extends downwardly to the lower construction of the frame where it is connected with the sash B in a manner to be later specified. This cord 25 finds its counterpart in a spring device 16 in the form of the cord 26 which is also wound on its winding drum and passes downwardly to the sash C. A helical spring 27 is coiled about the shaft 22 and has one end anchored to the shaft as shown at 28, while its other end is made fast to the bracket 17, as indicated at 29.

Referring now with more particularity to the construction of the side portions of the frame A, it is noted that the side frame 13 includes a side piece 30 which has parallel front and back faces 31 and 32, a side face 33 perpendicular thereto and an irregular generally inclined surface between the front and back faces 31 and 32 and which surface faces inwardly of the window frame. Referring now more particularly to Figs. 3 and 6, it is noted that this irregular inclined portion includes a groove 34 adjacent the front face 31 which groove is designed to accommodate the central portion of a hinge as will be later described. A narrow plane face 35 connects the groove 34 with a cutaway portion 36 that has centrally formed therein a circular groove 37 coextensive with the side piece 30. In fact, all of the grooves, surfaces, and cutaways now being described extend the full length of the side piece. At its other side the cutaway 36 is spaced from a face 38 that is parallel to the front and back faces 31 and 32 by a narrow surface 39. Adjacent the free edge of the face 38 a groove 40 is formed which corresponds to the groove 34 in that it accommodates the central portions of the hinges of the upper sash member C. A narrow strip 41 connects the groove 40 with a cutaway 42 which is also formed with a circular groove 43 centrally thereof. The other edge of the cutaway 42 is spaced from the edge of the rear face 32 by a narrow strip 44. A back piece 45 may be secured to the side piece 30 over the face 32 to provide a projecting flange surface 46 which constitutes a guide for the sash C, as will be later described. A front piece 47 may be included in the construction of the side frame 13 and this piece partially extends over the front face 31.

A metallic lining or guide is positioned in the cutaway 36 and groove 37 and comprises side flanges 48 and 49 which are spaced apart by a slot 57 and narrow strips 35 and 39. These side flanges are connected by a

tubular portion 50 which constitutes a lining for the circular groove 37. At the lower end of the side frame and coextensive with the lower sash B, when the latter is in lowered position, the side flange 49 is formed with an outwardly projecting strip or flange 51 that constitutes a weather strip and cooperates with the sash B, as will be later described to provide a good protective seal against weather conditions. A second metallic lining for the cutaway 42 and groove 43 is provided and this is a substantial duplicate of that already described, having the side flanges 52 and 53 which are spaced apart by a groove 54 and which lie flush with the strips 41 and 44. These side flanges 52 and 53 are connected by a tubular portion 55 that lines the groove 43. In connection with this guide, the side flange 53 is provided at its upper portion with an out-turned flange 56 that is coextensive with the upper sash C and cooperates therewith as a weather strip to afford protection against the weather.

Referring now to the construction of the side frame 12 at the other side of the window it is noted that this frame includes a side piece 58 that extends the whole length of the window. This piece 58 has parallel front and rear faces 59 and 60 which are connected at one side by a side face 61 perpendicular thereto and at the other by an irregular series of inclined surfaces now to be described. These comprise a short inclined face 62 adjacent the edge of the front face 59 which is connected with a similar narrow inclined face 63 by a groove 64. Offset from this face 63 and connected thereto by a surface 65, parallel to the front and rear faces 59 and 60, is a narrow strip 66 which is connected to a similar narrow strip 67 adjacent the rear face 60 by a groove 68. A back piece 69 is included in the construction of the side frame 12 and has a portion projecting beyond the strip 67 to provide a guiding surface 70 for the upper sash C. The grooves 64 and 68 are provided with metallic linings as shown at 71 and 72.

The sash B carries at one side a hinge and slide device adapted for cooperation with the tubular guide 57 and at its other side a movable tongue arrangement that cooperates with the guide 71. The sash B comprises a frame member having side pieces 73 and 74 and top and bottom pieces 75 and 76, respectively. These frame pieces 73, 74, 75 and 76 carry a pane of glass designated 77 which may be mounted therein in the well-known manner. The side piece 73 has an inclined face 78 designed to engage and lie flat against the flat surface defined by the strips 35 and 36 and flanges 48 and 49. This inclined surface 78 is formed with a narrow groove 79 that is substantially perpendicular to the inclined face 78 and this groove 79 receives the weather strip 51 when the sash B is in

closed or sliding position. The hinge part 80 is sunk in the face 78 so that its outer surface lies flush therewith and is securely fastened to the side piece 73 through the means of screws 81. A second hinge part 82 is connected to the side piece 73 in a like manner and is spaced from the hinge part 80. 70

A guide rod 83 is formed with curved portions 84 that extend through the slot 57 and are integrally connected with hinge parts 85 and 86. The hinge parts 85 and 86 are connected with the hinge parts 80 and 82 in the usual manner, such as by pins 87 passing through the interfitting bored portions shown at 88. The cord 25 which is taken up in the drum 23 extends downwardly into the tubular guide 50 and is connected to the upper end of the guide rod 83 as shown at 89. It is evident that the spring 27 ordinarily exerts an influence through the cord 25 to offset the weight of the sash B and accompanying parts. 85

This sash B may be swung into position with the inclined face 78 engaging the flat surface previously mentioned and in which position the exterior face 90 of the sash engages the face 38 of the frame. In this position the face 38 constitutes a guide, that cooperates with the guide rod 83 and guide 50 to control the sliding action of the sash. When in this sliding position the weather strip 51 fits in the groove 79 in such manner as to admit of the sliding action on the part of the sash. The sash may be swung outwardly, as shown in Fig. 6, to provide access to the exterior surface thereof, pivoting about the pins 87 during such swinging action. The bottom sill 11 may be provided with a weather strip, shown at 91, which projects upwardly and fits in a groove 92 formed in the bottom piece 76 of the sash. 100

Referring now more particularly to the mechanism carried by the side piece 74 of the sash B, particular attention is directed to Figures 3, 4, and 5. The side piece 74 has inclined surfaces 93 and 94 which are complementary to the inclined surfaces 62 and 63 on the side piece 58 and which are separated by a groove designated 95. Operatively mounted in the groove 95 is the mechanism which provides a locking guide which projects into the groove member 71 and which takes the form of a U-shaped channel member 96. This channel member 96 is positioned with its open face disposed inwardly of the groove 95 and its curved nose 97 engaging with the tubular guide 71 when the sash is in normal sliding position. An upper link member 98 clearly shown in Fig. 5 is pivoted at 99 between the side walls of the channel member 96. At its other end the link member 98 is pivotally connected as shown at 100 to a bracket member 101. This bracket member 101 has side walls 102 which are connected by an end wall 103. The latter 110

115

120

125

130

is formed with openings 104, while the side walls 102 are formed with over-turned flanges 105 which are also formed with screw openings (not shown). Fastening members 5 in the form of screws pass through the openings in the side members 105 and the openings 104 to positively secure the bracket 101 to the side piece 74 of the sash B and in the groove 95. Spaced from the upper link 10 member 98 and adjacent the lower end of the sash B a second link member 106 is pivotally mounted to the channel member 96 in the manner described with respect to the upper link 98 and as shown at 107. The 15 other end of this link 106 is pivotally connected as shown at 108, to a second bracket member 109, this latter bracket being a substantial duplicate of the upper bracket member 101 and mounted in the groove 95 in the 20 manner above described. These links 98 and 106 are always in parallel relationship and affect the channel member 96 when the latter is moved either upwardly or downwardly to induce movement inwardly or outwardly of 25 the groove 95, this being due to the toggle effects of these spaced links 98 and 106.

A coil spring 110 has one end anchored in the bottom of the groove 95, as shown at 111, and its other end is anchored between the 30 walls of the channel member 96, as shown at 112. This spring 110 normally urges the channel guide 96 upwardly which tendency, in conjunction with the effects of the links 98 and 106, urges the rounded nose 97 into 35 the groove guide 71. It is evident that the channel member 96 may be moved downwardly under the influence of mechanism to be hereinafter described to cause retraction of the nose 97 from the groove 71. This 40 downward movement on the part of the channel member 96 is provided for by the notched arrangement shown at 113 which insures proper pivoting movement of the link members 98 and 106.

45 The lower portion of the side piece 74 is cut away at 114 to accommodate the actuating mechanism for the channel member 96. This mechanism includes a pin 115 which is carried by the channel guide 96 adjacent its open 50 edge and projects into the cutaway space 114. A cam member 116 is pivotally mounted, as shown at 117, in the side piece 74. This cam member 116 has a curved surface 118 which normally engages the pin 115, so that when 55 the cam member is swung downwardly the pin is moved downwardly and thereby draws the channel member 96 down. A stem 119 projects outwardly from the free extremity of the cam 116 and is notched as shown at 120 60 to accommodate a plate 121. This plate 121 closes the cutaway portion 114 and lies flush with the surface of the window sash. This plate 121 is provided with an arcuate groove 122 which receives the notched portion of the 65 stem 119. This stem carries at its outer ex-

tremity an operating member in the form of a knob 123. This knob may be grasped by an operator to move the stem 119 through the slot 122 whereby the cam member 116 is turned on its pivot 117 to urge the pin 115 70 and the channel member 96 downwardly to retract the rounded nose 97 from the groove 71.

The operation of the lower sash B may be briefly outlined as follows:—When the 75 window is in sliding position, the nose 97 of the channel member 96 projects into the groove 71 and the weather strip 51 is received in the groove 79. The sash may be now raised or lowered in the customary manner. If it 80 is desired to obtain access to the exterior surface of the sash, say for the purpose of washing the outer face of the window-pane 77, the knob 123 is grasped and swung over the plate defined by the arcuate slot 122. As previously pointed out, this operation closes the cam 116 to affect the pin 115 to cause downward movement of the channel member 96. This downward movement is controlled by the pivoted links 98 and 106 to cause retraction 85 of the nose 97 from the groove. The window may now be swung outwardly into the desired position. It is evident that the sash B may be swung out even when the sash is in an upraised position with respect to the 90 frame A as all the parts are designed to accommodate this movement.

The construction of the sash C is a substantial duplicate of that already described. This sash is provided with a groove which is 100 a counterpart of groove 79 in the sash B and which cooperates with the weather strip 56. The only appreciable distinction between the design of the sash C and sash B is that the plate 121 is countersunk below the surface of 105 the side piece of this sash. In this instance the operating member 123 lies entirely beneath the plane of the front surface of the sash, this arrangement being availed of so as to prevent any interference between the sliding movements of the sashes B and C. The sash C slides under the guiding action of the guide rod in the tube 43 and the guiding effects of the projecting flange surface 46 of the member 45. It is notable that the sash C is of 110 slightly narrower dimensions than the sash B and for this reason they both may be swung outwardly when superimposed one above the other.

The arrangement of springs provided in 115 lieu of the usual counterweights is desirable in that it eliminates the need for having a comparatively large frame construction. When these springs are eliminated and counterweights employed, it is necessary that 120 the side frames 12 and 13 be of sufficiently large dimensions to provide space in which the weights operate.

125 It is evident from the foregoing that I have provided a window which includes sashes 130

which may be raised or lowered in the usual manner and each of which may be swung inwardly in any position. Also the various instrumentalities provided for effecting this 5 action are of such design as to insure proper operation of the window sashes at all times.

While a preferred specific embodiment of the invention is hereinbefore set forth, it is to be understood that I am not to be limited to 10 the exact constructions illustrated and described because various modifications of these details may be provided in putting the invention into practice within the purview of the appended claims.

15 I claim:

1. A fastening device for holding a window sash in weighted frictional engagement with a sash frame, comprising a U-shaped channel bar mounted in a groove in the sash 20 and having its curved edge normally projecting laterally from the groove for making frictional binding engagement with a groove in the frame, a plurality of toggle link members pivotally mounted at one end 25 to the interior of the channel bar and at its other end to the sides of the groove in the sash, said members being parallel with each other in their movement on their pivots, tactile resilient means in connection with 30 the channel bar and the sash for normally drawing said bar upwardly against the toggle action of the links, whereby to cause lateral extension of the bar from the groove of the sash, a pin projecting across the channel bar, and camming means mounted on the sash for guiding said pin which upon downward movement effects a toggle movement of the bar inwardly and downwardly in the 35 groove toward the longitudinal axis of the sash and release the frictional engagement 40 with the frame, said channel bar having spaced recesses in one of its side walls for insuring pivotal movement of said link members during the downward movement of the 45 bar into the sash groove.

2. In a window-sash and frame construction, the improvement comprising a U-shaped channel bar movable in a groove in one side of the sash, and coextensive with 50 the length of said side, a plurality of spaced toggle members pivotally connected at one end to the side walls of the channel bar, and at the other end to the side walls of the groove of the sash, to permit toggle movement of the bar from the groove in the sash to a groove in the window frame, a resilient spring member normally under tension in connection with the bar and the wall of the 55 groove in the sash for forcing the bar upwardly and outwardly of the groove of the sash, against the action of the toggle members as pivots, forming a frictional binding engagement with the groove in the window frame, and means on the sash in connection 60 with the bar for actuating the same against 65

the tension of the spring member and permit resultant inward and downward movement of bar against the groove of the sash.

In testimony that I claim the foregoing as my invention, I have signed my name here- 70 to.

ALFRED YUDES.
